UNITED STATES PATENT OFFICE.

VLADIMIR SHAVITCH, OF CARMEL, CALIFORNIA.

INNER TUBE.

1,270,223.

Specification of Letters Patent. Patented June 18, 1918.

Application filed August 10, 1917. Serial No. 185,535.

To all whom it may concern:

Be it known that I, VLADIMIR SHAVITCH, a citizen of the United States, residing at Carmel-by-the-Sea, in the county of Monterey and State of California, have invented new and useful Improvements in Inner Tubes, of which the following is a specification.

This invention relates to an inner tube 10 for pneumatic tires.

An object of the invention is to produce an inner tube for tire casings comprising any desired number of cells or air compartments having means for simultaneously inflating all of the compartments but providing valves for closing all of the compartments, so that should one or more of the compartments become deflated by puncture or from other causes, the outer and inflated 20 compartments will not be interfered with.

It is a further object of the invention to produce a pneumatic tube having arranged therein a plurality of spaced partitions dividing the tube into a number of air compartments, each of the partitions being formed with an opening which is normally closed by a valve, all of the valves being connected and being under spring tension whereby the same will be normally retained 30 seated, means being secured to the connecting means for simultaneously unseating all of the valves to permit of the inflation of all of the compartments.

It is a further object of the invention to produce an inner tube embodying a plurality of independent air cells or compartments, in which injury to one of the said cells or compartments will not interfere with the remaining cells or compartments, in 40 which the construction shall be of a comparatively simple nature, cheap to manufacture, and thoroughly efficient for the purpose designed.

Other objects and advantages will appear 45 as the nature of the invention is more fully understood, reference being had to the accompanying drawings, in which,

Figure 1 is an approximately central longitudinal sectional view through an inner tube constructed in accordance with the present invention.

Fig. 2 is a detail sectional view illustrating the manner of unseating the valves of the separate compartments of the tube, when the tube is to be inflated.

Fig. 3 is a transverse sectional view approximately on the line 3-3 of Fig. 1.

The improved inner tube is broadly indicated by the numeral 5, and may be of the ordinary rubber construction. The tube is 60 interiorly formed with a plurality of transverse partitions 6, whereby the said tube is divided into any desired number of air cells or compartments 7. The partitions may be of any material best suited for the purpose 65 devised, such for instance, as a rubber fabric and one of the partitions, indicated for distinction by the numeral 8 is preferably, but not necessarily of a greater strength or rigidity than the remaining partitions 6. 70 Each of the partitions is provided with an opening 9, and preferably the said opening is reinforced by a metallic sleeve or collar 10, the ends of the same being flanged so as to contact with the outer faces of the 75 partitions 6. Passing through the collar 10 are the stems 11 of valves 12. Preferably both the stems and the valves are of metal, but the inner or contacting faces of the said valves 12 have arranged thereon, a compressible disk 13 which, when contacting with the flange of the collars will compress to prevent the escape of air between the valve and seat. The partition 8, upon its opposite sides has secured thereon eye members 14 receiving the end convolutions of springs 15-15, and to the opposite ends of the said springs 15 are secured wires or other flexible elements 16 which are also connected with the stems of the valves near 80 the said springs. In a like manner, the outer ends of the valves are provided with eyes 17, between the said eyes and the stem of the adjacent valve is secured a flexible element or wire 18, in this manner all of 85 the valves are connected. The compartment 7 diametrically opposite the partition 8 is provided with the usual spring pressed valve in the nature of a plunger 19, and to which the inflating pipe is connected. This 90 plunger valve 19 upon its inner end is provided with oppositely extending arms having eyes 20 and to these eyes are secured the end flexible elements 21 of the valves closing 95 the openings or valve seats in the partitions 105 of the said end compartment 7. By reference to the drawings, it will be noted that the valves are arranged in opposite directions, which for the sake of distinction are indicated by the numerals 22 and also that the 110

openings and valve seats are so arranged that the connecting members between the valves will exert a straight pull on all of the valves when the member 18 is forced inwardly against the springs. When pressure of the member 18 is relieved, the springs 15 exerting a pressure in an opposite direction, will pull upon the connecting elements 16 secured directly to the said springs to draw the valves connected by the said elements 16 diametrically upon their seats and by virtue of the connecting element 18 between the remaining valves all of the latter will be positively seated.

From the foregoing description, when taken in connection with the accompanying drawings, the simplicity and advantages of the construction will be apparent, it is thought, without further detailed description.

Having thus described the invention, what I claim is:

1. A pneumatic tube having a plurality of spaced partitions therein dividing the said tube into independent compartments, each of said compartments having an opening, a valve for the opening, connecting means be-

tween the valves, spring means between certain of the connecting means and one of the partitions for normally seating all of the valves, an inflating valve in one of the compartments, a spring pressed plunger arranged through the said valve, and connecting means between the said plunger and the valves opposite thereto.

2. A pneumatic tube having spaced inner partitions dividing the said tube into a plurality of air compartments, each of said compartments having an opening, a metallic flange collar in the opening, a valve having a stem passing through the collar, a compressible element upon the inner face of the valve, helical springs secured to the opposite walls of one of the compartments, a flexible connection between the springs and the valves adjacent thereto, a flexible connection between the remaining valves, an air inlet valve in one of the compartments, a spring pressed plunger passing through the valve and connected to the flexible element of the valves in the said compartment.

In testimony whereof I affix my signature.

VLADIMIR SHAVITCH.
